(57) **CLAIM**

We claim the ornamental design for the toy with a flying top, as shown and described.

DESCRIPTION

FIG. 1 is a left side view showing our new design for the toy with a flying top, the right side view being a mirror image thereof;

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a left side view showing the design with its parts in a separated state, the right side view being a mirror image thereof;

FIG. 7 is a front view of FIG. 6;

FIG. 8 is a rear view of FIG. 6;

FIG. 9 is a top view of FIG. 6; and,

FIG. 10 is a bottom view of FIG. 6.
